DESIGN FOR A COMBINED CIGARETTE CONTAINER AND ASH TRAY OR SIMILAR ARTICLE

Alfred I. Hollander, Deal, N. J.

Application October 2, 1943, Serial No. 111,254

Term of patent 7 years

To all whom it may concern:

Be it known that I, Alfred I. Hollander, a citizen of the United States and a resident of Deal, in the county of Monmouth and State of New Jersey, have invented a new, original, and ornamental Design for a Combined Cigarette Container and Ash Tray or Similar Article, of which the following is a specification, reference being had to the accompanying drawing, forming part thereof.

I claim:

The ornamental design for a combined cigarette container and ash tray or similar article, as shown.

ALFRED I. HOLLANDER.
